(57) CLAIM

We claim the ornamental design for a container lid comprising frustum shaped sidewall and seaming chuck receiving radius, as shown and described.

DESCRIPTION

FIG. 1 is an isometric top view of a container lid comprising frustum shaped sidewall and seaming chuck receiving radius;

FIG. 2 is an enlarged detail view of area 2 circumscribed within FIG. 1;

FIG. 3 is an isometric bottom view thereof;

FIG. 4 is an enlarged detail view of area 4 circumscribed within FIG. 2;

FIG. 5 is a top plan view thereof;

FIG. 6 is an enlarged detail view of area 6 circumscribed within FIG. 5;

FIG. 7 is a bottom plan view thereof;

FIG. 8 is an enlarged detail view of area 8 circumscribed within FIG. 7;

FIG. 9 is a front view thereof;

FIG. 10 is a side view at 45 degrees to the left from the front view thereof;

FIG. 11 is a left side view thereof;

FIG. 12 is a rear view thereof;

FIG. 13 is a right side view thereof;

FIG. 14 is a sectioned elevation left side view thereof, the section being taken in a direction of section line 14-14 of FIG. 5;

FIG. 15 is an enlarged detail view of area 15 circumscribed within FIG. 14;

FIG. 16 is a sectioned elevation 45 degree to the left from the front side view thereof, the section being taken in a direction of section line 16-16 of FIG. 5;

FIG. 17 is an enlarged detail view of area 17 circumscribed within FIG. 16;

FIG. 18 is a sectioned elevation left side view thereof, the view illustrating an exemplary nesting capability thereof;

FIG. 19 is an isometric top view illustrating the container lid comprising frustum shaped sidewall and seaming chuck receiving radius seamed to the exemplary container;

FIG. 20 is a sectioned elevation left side view thereof, the view illustrating the container lid comprising frustum shaped sidewall and seaming chuck receiving radius seamed to an exemplary container;

FIG. 21 is an isometric top view of second container lid comprising frustum shaped sidewall and seaming chuck receiving radius comprising formations and elements integral with a bottom wall to illustrate nesting of modified container lids;

FIG. 22 is an isometric bottom view of the second container lid thereof;

FIG. 23 is a sectioned elevation front view of the second container lid thereof;

FIG. 24 is a sectioned elevation front view of the second container lid thereof, the view illustrating an exemplary nesting capability thereof;

FIG. 25 is an isometric top view illustrating the enhanced variant thereof seamed to the exemplary container; and,

FIG. 26 is a sectioned elevation left side view of the enhanced variant thereof, the view illustrating the second container lid thereof seamed to an exemplary container. The evenly spaced broken lines in the drawings depict portions of the container lid comprising frustum shaped sidewall and seaming chuck receiving radius that form no part of the claim.
